UNITED STATES PATENT OFFICE.

LESLIE R. McDONALD, OF MONTREAL, QUEBEC, CANADA.

DISPLAY APPARATUS.

Application filed March 3, 1926. Serial No. 91,877.

My invention relates to that class of display apparatuses wherein flexible placards are wound around a rotatable holder and are released and allowed to unroll, one by one, 5 and successively drop into view position, particularly to that class of such apparatuses wherein the rearmost placard is lifted bodily so as to facilitate its falling forward over the carrier and unrolling to expose its face; 10 and my improvements are directed to means whereby the hanging placards, with the exception of the rearmost one, are positively gripped and held so as to prevent their being carried up out of their order under the 15 influence of the rearmost placard when it is raised.

Other objects of my invention are to facilitate the hanging of the placards vertically instead of sloping forward toward their bottom; to intermittently release and grasp the 20 placard pack as the carrier turns step by step; and to secure these results by novel mechanism as will be hereinafter pointed out and explained.

This improvement is adapted for application to a display apparatus of the type illustrated in my Letters Patent No. 1,567,281, of December 29th, 1925, the placard carrier and the carrier rotating means 25 being similar to those shown in my said patent, for which reason I have not illustrated them again in detail in this application.

In the drawings, Fig. 1 is a front view of an apparatus illustrating the embodiment of my improvements; Fig. 2 is a vertical sectional view, on an enlarged scale, taken as on the line 2—2 of Fig. 1, looking to the right, medial portions being omitted to shorten the view, and part of one of the plates and of 30 the end of the placard carrier being broken away the better to show the construction beyond them; Fig. 3 is a detail, on a still further enlarged scale, of the sheet gripping mechanism, taken as looking to the left on Fig. 2, medial portions being broken out for the purpose of saving space; Fig. 4 is a view of the same, taken as looking to the right on Fig. 3, part of one of the wing plates and bearing rod being broken away 35 for clearness; Fig. 5 is a plan view of the sheet gripper, taken as looking up on Fig. 4; and Fig. 6 is a diagrammatic illustration of the manner in which the sheets are held between the bearing rod and gripper.

In all the figures similar parts are designated by corresponding reference numerals.

The case 1 is of any suitable or conventional form, and is provided with an open or glazed front 2, as is customary in apparatuses of this character. The placard carrier 3 corresponds to the composite placard carrier 11, 12, 13 of my aforesaid patent, and is mounted and operated in the same manner, being hung from a transverse bar 5 by arms 15, only one of which is shown in the drawings, carrying the ends of the axle 16 of the carrier, one of the arms being provided with an extension 17 carrying a roller 19 traveling on a cam 4 on a shaft 39. A shaft 22 is mounted rotatably in bearings 60 in the frame, and is provided with one or more lifting rollers 23 preferably of soft rubber. A pawl 24 is hung on the bar 5; and another pawl 29 is pivoted in the end of the case. The pawls engage the teeth on 65 the disk-end 38 of the carrier. The shaft 22 is driven anti-clockwise, and the shaft 39 clockwise, through suitable gearing from a source of power. The rotation of the cam 4, through the roller extension 17 and arms 70 15, causes the placard carrier to swing forward and back, and, under the control of the pawls 24 and 29, to be rotated step by step. The swinging of the placard carrier carries it away from, or back to the rollers 23, 75 which, on the back swing of the carrier, engage the rearmost placard and lift it upward and forward. These operations are 80 fully described in my aforesaid patent. The cam 4 corresponds to the cam 27 of my aforesaid patent. 85

In my present improvement, 6 is a lever, pivoted at 7 to the end frame 8 mounted in the case, one end of the lever being provided with a roller 9 against which the cam 4 90 travels, and the other end, 10, of the lever being pivoted to a rod 11, the lower end of which is, in turn, pivoted to an arm 12, carried by a rod 13, journalled in arms 14, 15, supported by the frame of the mechanism. 100 A bearing rod 18 is secured between the lower ends of the arms 14 and 15, and is disposed so that the placards shall hang down close in front of it. Suitable means, such as a coiled spring 20, fastened at one end of the shaft 13 and anchored at the other end to the carrying arms, as through a transverse bar 21, operates to normally turn the shaft 13 so that the roller 9 is kept to duty 105 against the cam 4.

Guide plates or wings 25, 26 are fastened to the respective ends of the hangers 14, 15, 110

and are disposed outside, one on each side, of the space occupied by the hanging placards.

From the upper and outer corner of each 5 guide plate a flange 27 or 28 is turned outward, as shown in the drawings, so as to form a notch in the corner of the guide plate, with an outwardly extending shelf beyond it.

10 On the shaft 13 are fastened two arms 30 and 31, which swing with the shaft, the mechanism being so adjusted that the movement of the arms is between the bearing rod 18 and the notches in the corners of the 15 guide plates.

On the end of these arms are pivoted sheet grippers 32, 33, each having two arms disposed at right angles to each other, one of them being adapted to slide against the 20 adjacent guide plate, while the other arm is projected out over the placard receiving space.

These grippers 32 and 33 are adjusted to have a normal inclination to rotate outward 25 against their adjacent guide plates, this result being obtained by suitable means such as springs 34, 35, each having one end anchored as on the shaft 13, and the other end connected with its cooperating gripper as by 30 entering the hole therein; the springs being tensed by being sprung over pins 36, 37 so as to cause the grippers to have a normal inclination to rotate outward.

If the shaft 13 is rotated so that the grippers rise above the level of the flanges 27, 28, the springs 34 and 35 will cause the grippers to rotate ninety degrees so that one end of each gripper will turn outward above and be raised upon a flange 27 or 28, and the other 40 end of the gripper will project upward, but outside of the area in which the placards lie.

The adjustment of the apparatus is such that the end of the last placard normally hangs just above and free from the bearing rod 18, while one end of each gripper is extended over in front of the hanging placards and is pressed back against them by the action of the cam 4 and the intermediate mechanism. The grippers and bearing rod thus 45 cooperate as downhold means for the placards between them. This leaves the rear-most sheet free to be lifted by the lifting mechanism, for instance, that illustrated in my aforesaid Patent No. 1,567,281, without displacing or disarranging the other placards because of the friction of the rear-most placard against the pack. When the placard has been lifted and is about to fall forward, it is necessary to remove the grippers from 50 the space into which the placard will fall. This is accomplished by the rotation of the cam 4, the smaller diameter of which, reaching the roller 9, allows that end of the lever 6 to swing up, thereby causing the shaft 13 to rotate and to raise the arms 30 and 31

until their grippers are above the flanges 27 and 28, respectively, when the grippers will rotate outwardly so as to stand outside of the placard receiving space. The placard then falls; the rotation of the cam 4 continuing reverses the movement of the shaft 13 and arms 30 and 31, lowering the arms until the grippers rest against the placard pack, and pressing thereagainst so as to prevent the disarrangement of the placards 75 during the next lifting operation.

It will be understood that the rotation of one step by the placard carrier again raises its rear-most placard above the bearing rod 18.

I wish it to be understood that the embodiment of my invention which I have illustrated and described is to be considered as a typical, and not as an exclusive, form. For as will be readily appreciated by those familiar with the art, the details of mechanism can be varied as by the use of equivalents, and the like, without departing from the spirit of my invention as described and claimed.

Having thus described my invention, what I claim and desire to secure by Letters Patent of the United States is:—

1. In a display apparatus, the combination of placard carrier rotating means and a rotatable placard carrier, a series of flexible placards each attached by one end thereto and partially rolled thereupon with their free ends depending therefrom, means for engaging and raising the rear-most placard, and downhold means for positively gripping all of the placards but the rear-most one.

2. In a display apparatus, the combination of placard carrier rotating means and a rotatable placard carrier, a series of flexible placards each attached by one end thereto and partially rolled thereupon with their free ends depending therefrom, means for engaging and raising the rear-most placard, and downhold means for alternately gripping and releasing all of the placards but the rear-most one.

3. In a display apparatus, the combination of placard carrier rotating means and a rotatable placard carrier, a series of flexible placards each attached by one end thereto and partially rolled thereupon with their free ends depending therefrom, means for engaging and raising the rear-most placard, and downhold means for gripping all the placards in front of the last one, while it is being raised, and alternately releasing the placards when the carrier is rotated.

4. In a display apparatus, the combination of placard carrier rotating means and a rotatable placard carrier, a series of flexible placards each attached by one end thereto and partially rolled thereupon with their free ends depending therefrom, means for engaging and raising the rear-most placard

successively, and downhold means, embodying resistance means disposed behind the placards, and cooperating pressing means engaging against the front of the foremost 5 placard, for positively gripping all of the placards but the rearmost one.

5. In a display apparatus, the combination of placard carrier rotating means and a rotatable placard carrier, a series of flexible 10 placards each attached by one end thereto and partially rolled thereupon with their free ends depending therefrom, means for engaging and raising the rearmost placard successively, and downhold means embodying 15 resistance means disposed behind the placards, and cooperating pressing means intermittently engaging against the front of the foremost placard, for positively gripping all of the placards but the rearmost 20 one.

6. In a display apparatus, the combination of placard carrier rotating means and a rotatable placard carrier, a series of flexible 25 placards each attached by one end thereto and partially rolled thereupon with their free ends depending therefrom, means for engaging and raising the rearmost placard,

downhold means embodying movable grippers, for engaging the hanging portions of the other placards and means for intermittently removing the movable grippers out of 30 the path of the forwardly falling placards.

7. In a display apparatus, the combination of means for supporting a plurality of 35 flexible placards; means for lifting and throwing over and forward, successively, the rearmost placards, and positively acting means for engaging the opposite sides of and gripping and holding down all but the rearmost placard during each lifting operation. 40

8. In a display apparatus, the combination of placard carrier rotating means and a rotatable placard carrier, a series of flexible 45 placards each attached by one end thereto and partially rolled thereupon with their free ends depending therefrom, means for engaging and raising the rearmost placard, downhold means, means for projecting the downhold means in front of and against the foremost placard, and means for intermittently withdrawing such downhold means, 50 the downhold means being actuated by the carrier rotating means.

LESLIE R. McDONALD.
